(54) **GRIST MILL, HORIZONTAL**

(76) Inventor: **Israel Kelsey**

Israel Hiltzey, Robertson, New
Letters Patent.

The Schedule referred to in these Letters Patent, forming
part of the same, containing a Description on the words
of the said Israel Hiltzey himself of his horizontal mill.

It is so constructed that it will go under water at any depth, without any sensible variation under any given head, but it is always preferred to be under water, when the water is at the lowest, etc, as for a tide mill where it is subject to inundation - it is so, constructed with a bed of sufficient, bigness for the wheel to extend round the wheel, and a passage or passages sufficient to contain water enough to drive a mill as occasion requires - sometimes, one passage is sufficient, and sometimes two are necessary, and it may be found necessary to have four - wheel passages are dug in the bed to receive water under the cylinder, sufficient to drive the mill, and when the water has passed the cylinder, the passages must be nearly gradual, until it gets round within the cylinder, running out at the passage, where the water
enters under the cylinder to raise the water up under the wheel
with its hydrostatisal power - the gate must be as near the cylinder as possible - the wheels proper for this apparatus are various, according to the particular use designed, and as occasion and circumstances require - the wheel is set in a box through which the shaft is put, the bigness of the box of the bed to the bottom of the shaft may answer the same purpose) within the passage for the water, and the buckets are placed nearly in a spiral form round the bed - in direct opposition to the side of the passage; or in some cases, it is best to have the wheel solid, except passages out thro' the wheel sufficient to receive the water from the passage, with a hook at the bottom to raise the water and then back in the same manner as the other wheel, the water is then delivered backward thro' the top of the wheel - the size

and proportion of the buckets and passages may vary according to circumstances - they are commonly about one fifth of the diameter of the wheel and the depth of the passages where they pass under the cylinder may be nearly double to the width - the width may be varied to a fourth or sixth of the diameter of the wheel, or what proportion best suits the situation. the greater the passages are in proportion to the wheel, the less hydrostatic power is acting under the load of the wheel - and the less the passages are in proportion, the more of such power is acting under the wheel - also the power of this apparatus is principally hydrostatical, especially the first wheel is mostly upon hydrostatical principles, without any loss of motion, except the bucket giving way to the water, in the same proportion as a wedge gives way to the pressure when it slips out,
